US00D777049S

(12) **United States Design Patent** (10) Patent No.: **US D777,049 S**
Barton et al. (45) Date of Patent: ** Jan. 24, 2017

(54) **DIAGNOSTIC ANALYZER**

- (71) Applicant: **Abbott Laboratories**, Abbott Park, IL (US)
(72) Inventors: **Christina A. Barton**, Irving, CA (US); **Vladlena Belozerova**, Philadelphia, PA (US); **Ami Marie Verhalen**, Sun Prairie, WI (US); **Jesse Charles Darley**, Madison, WI (US); **Sherry Sue Eckholm**, Sun Prairie, WI (US)
(73) Assignee: **ABBOTT LABORATORIES**, Abbott Park, IL (US)

(**) Term: **15 Years**

(21) Appl. No.: **29/531,578**

(22) Filed: **Jun. 26, 2015**

(51) LOC (10) Cl. **10-04**

(52) U.S. Cl.
